UNITED STATES PATENT OFFICE.

WALTER S. GOODWILLIE, OF CHICAGO, ILLINOIS, ASSIGNOR TO D. M. GOODWILLIE CO.,
OF CHICAGO, ILLINOIS, A CORPORATION OF ILLINOIS.

BOX.

1,234,152.

Specification of Letters Patent. Patented July 24, 1917.

Application filed December 31, 1915. Serial No. 69,647.

To all whom it may concern:

Be it known that I, WALTER S. GOODWILLIE, a citizen of the United States, and a resident of Chicago, in the county of Cook and State of Illinois, have invented certain new and useful Improvements in Boxes, of which the following is a specification.

My invention relates to boxes or cases for supporting bottles and it relates particularly to that class of boxes sub-divided into bottle receiving compartments and intended for use in storing or delivering bottles.

Ordinary boxes or cases have been built for various kinds of bottles but such cases do not possess the required strength and thus fail to afford ample protection, and they are also more or less unsanitary in that they cannot be readily cleansed. Take for example cases to be used in the handling and delivery of milk in bottles. These boxes or cases are usually open at the top and are more or less roughly handled and consequently the boxes must possess great strength. They must also be so constructed that they can be thoroughly and efficiently cleaned to be kept in sanitary condition, as during the handling of milk more or less drops into the case and dirt has also a tendency to collect in the corners.

The important object of my invention is to produce a strong and rigid bottle containing case sub-divided into pockets for the individual reception of bottles and having an open bottom which lessens the chances of dirt settlement and which allows the case to be quickly and thoroughly flushed out and cleaned. The invention will be better understood when described in connection with the accompanying drawing in which—

Figure 1 is an under side view of a box involving my improved features;

Fig. 2 is a sectional view on plane 2—2,

Fig. 1,

Fig. 3 is a sectional view on plane 3—3,

Fig. 2,

Fig. 4 is a fragmentary perspective view of one corner of the box, and

Fig. 5 is a fragmentary perspective view of a longitudinal and a transverse partition board showing the manner in which they are interlocked and jointed together.

The box shown has side walls 10 and 11 and the end walls 12 and 13, the end walls being rabbeted as indicated at 14 for receiving the ends of the side walls, the end

and side walls being secured each to the other as by means of nails 15 and 16. On their inner sides and at the lower sections thereof the side and end walls have the vertical grooves 17 and 18 respectively, these grooves being spaced to receive the ends of longitudinal and transverse partition members 19 and 20 respectively, these partitions forming the rectangular pockets *p* each of a size to receive one bottle. As best shown in Figs. 3 and 5, the longitudinal and transverse partitions are interlocked and jointed together to thus form a rigid pocket construction. As shown, the longitudinal partitions have the slots 21 extending half-way up from their lower edges and the transverse partitions have the slots 22 extending half-way down from their top edges. The slots 22 are of less width in the direction of the partition than the thickness of the longitudinal partitions, and the longitudinal partitions above the slots 21 therein are grooved on opposite sides as indicated at 23 and 24, the thickness at such grooves being substantially the same as the width of the slots 22. In the construction shown, the slots 21 in the longitudinal partitions are of a width substantially equal to the thickness of the transverse partitions. With this construction, when the longitudinal and transverse partitions are fitted together the slots 21 of the longitudinal partitions receive the lower sections of the transverse partitions below the slots 22 and the sections of the longitudinal partitions between the grooves 23 and 24 fit snugly into the slots 22, the grooves receiving the edges of the transverse partitions adjacent the slots 22, the partitions being then securely interlocked and snugly interjointed to form rigid and strong individual pockets. The longitudinal and transverse partitions can be separately inserted into the side and end wall grooves 17 and 18, or the partitions can be first interlocked and interjointed and the resulting pocket structure inserted as a whole into place between the side and end walls of the box.

In accordance with my invention I do not provide a continuous bottom for the box, 105 preferably keeping the bottom open as much as possible in order to reduce chances for accumulation of dirt and for facilitating cleaning and insuring sanitation. I provide just enough bottom to afford sufficient 110

seating area for the bottles in the pockets and for holding the partitions in place. As shown on the drawing, the grooves 17 and 18 are sufficiently longer than the height of 5 the partitions that when the partitions have been inserted there will be space for strips 25 below the ends of the transverse partitions and within the lower edges of the box sides 10 and 11. These strips are rigidly 10 secured to the sides as by means of nails and lock the transverse partitions in place in the box. I also provide intermediate longitudinal strips 26, these intermediate strips running parallel with and below the longitudinal partitions, and preferably their ends are extended into recesses 27 in the box ends 15 to form secure jointure therewith, the box ends being preferably nailed to the strips as indicated at 28, and the strips being also 20 nailed to the partitions as indicated at 29. The intermediate strips are sufficiently wider than the thickness of the longitudinal partitions in order that they may provide supporting surfaces 30 for the bottles in the 25 pockets, the outer strips 25 forming seating surfaces for the outsides of the side pockets. Thus only sufficient bottom is provided in the box to securely support the bottles in the pockets while at the same time the strip 30 arrangement disclosed serves to strengthen the box and to lock the pocket partitions therein. The bottom being thus open, the box can be readily cleaned in any desired manner as by flushing out with a stream. 35 In smaller boxes the side and intermediate longitudinal strips will be sufficient, but in larger boxes or those requiring greater strength transverse strips 31 may be provided, and these strips will be below and parallel with the transverse partitions, and the longitudinal and intermediate strips and these transverse strips will preferably be interjointed. In the drawing I have shown such transverse strip secured below the middle 40 transverse partition and this strip has the grooves 32 in its upper side while the intermediate longitudinal strips have corresponding grooves 33 in their upper sides, these grooves serving to rigidly joint the strips together. The transverse strips may also be nailed to the transverse partitions as indicated at 34 and may also be nailed to the box sides as indicated at 35. Where 45 transverse strips are used additional seat- 50

ing surface will be provided in the pockets 5 for the bottles.

The box of my invention by having its various parts securely jointed and nailed together is very strong and durable and particularly adaptable for resisting the rough usage to which boxes of this class are subjected and to amply protect the contained bottles during such usage. The box parts and the partitions and strips can be slotted and grooved by the ordinary machines 65 and can then be readily and quickly fitted and interlocked and secured together. As before stated, the open bottom makes the box much more sanitary and also takes off considerable of the weight. In the drawing 70 I have shown the ordinary hand-holes 36 in the end walls by means of which the box can readily be handled.

I do not, of course, desire to be limited to the exact and precise constructions and arrangements shown and described as changes and modifications are no doubt possible which would still come within the scope of the invention. I claim the following:

In a box, the combination with side and end walls rigidly secured together, said walls having spaced vertical straight slots on their inner faces extending upwardly a distance from the lower edges of the walls, longitudinal and transverse partitions intersecting and jointed together and engaging at their ends in said slots and sub-dividing the box into a plurality of pockets, side strips secured to the side walls below the transverse partitions and above the lower edges 80 of the side walls, intermediate longitudinal strips secured to the end walls above the lower edges thereof and running below the longitudinal partitions, a transverse strip secured to the side walls above the lower 85 edges thereof and interjointed with said intermediate longitudinal strips and running below the central transverse partition, said strips being of a width to project just a sufficient distance beyond the sides of the partitions to afford side supports for bottles placed within the pockets and to leave the pockets practically open at their lower ends. 90 95 100

In witness whereof I hereunto subscribe my name this 28th day of December, A. D. 1915.

WALTER S. GOODWILLIE.
